TEST TUBE RACK

Nicholas J. Fish, Youngstown, Ohio, assignor of one-half
to Arthur E. Rappoport, Youngstown, Ohio

Filed Oct. 3, 1966, Ser. No. 4,137

Term of patent 7 years

(Cl. D16—1)

FIGURE 1 is a perspective view of a test tube rack showing the front, the top and one side thereof.

FIGURE 2 is a vertical section on line 2-2 of FIGURE 1. The bottom, the side and the back not shown, are substantially plain.

I claim:

The ornamental design for a test tube rack, as shown and described.
